United States Patent

Des. 240,222
Patented June 8, 1976

240,222

APPOINTMENT CARD

John W. Cuozzo, Montclair, N.J., assignor to
C Co., Glen Ridge, N.J.

Filed July 30, 1974, Ser. No. 493,651

Terms of patent 14 years

Int. Cl. D19—08

U.S. Cl. D19—6

The figure is a front perspective view of an appointment card of conventional thickness showing my new design. The opposite side is unornamented.

I claim:

The ornamental design for an appointment card, substantially as shown and described.
